JOHANNES SAHL, OF WIESBADEN, GERMANY.

TRAVELING REQUISITE IN BAG FORM.

1,056,218.

Specification of Letters Patent. Patented Mar. 18, 1913.

Application filed July 5, 1912. Serial No. 707,763.

To all whom it may concern:

Be it known that I, JOHANNES SAHL, manufacturer, a citizen of the German Empire, and resident of Wiesbaden, in the 5 Province of Hesse-Nassau, Kingdom of Prussia, Germany, (whose post-office address is Wilhelmstrasse 42, Wiesbaden,) have invented certain new and useful Improvements in Traveling Requisites in Bag Form; 10 and I do hereby declare the following to be a full, clear, and exact description of the invention, such as will enable others skilled in the art to which it appertains to make and use the same.

15 This traveling requisite in bag form is a novelty whose unique arrangement absolutely guarantees the articles packed within it against breakage while at the same time compressing them within the smallest possible compass. In spite of its flexibility the bag stands firmly, rendering damage from leaking bottles quite impossible.

By this innovation toilet articles and appliances such as bottles, brushes, combs, files, 25 knives, etc., are stored in the form of a star along the side of the bag with the aid of pockets, pouches or other suitable receptacles, and in the center conveniently fastened to the bottom of the bag is fitted another 30 receptacle of flexible material *e. g.* a second bag to hold the sponge, friction towels, washing flannel, drying towel, and other flexible articles. This grouping of the toilet articles star fashion within a bag around a 35 central flexible receptacle absolutely insures them against breakage, at the same time keeping them together and in the smallest possible compass. Moreover by this arrangement of the fittings there is the further 40 advantage that, on placing the bag in position, a good standing-base is created, whose form can be increased by a corresponding arrangement of the bottom of the bag. This gives the bag the necessary stability,

when it is opened, so that, when using the 45 toilet articles, especially when manipulating with opened bottles, there is no possibility of any damage being done to the bag.

The annexed drawings give an exact reproduction of the invention. 50

Figure 1 shows the bag shut, Fig. 2 shows the bag opened, together with the toilet articles.

As will be seen from Fig. 2 the toilet fittings A, B, C, D, E, F, G, H, I, are fastened 55 by means of pouches (K) to the side of the bag (L) in such a way that they lie in star formation around the central receptacle (M) which serves to hold a sponge or other flexible toilet articles. The nature of the 60 fittings and their particular grouping does not affect the principle of the invention, nor is the shape of the bag, its outward dressing or material a matter of importance. For fastening the bag arrangements of a very 65 diverse character may be employed, these depending on the nature of the bag and its contents.

Having thus described the invention, 70 what is claimed as new is—

A receptacle for toilet articles consisting of a pouch bag having flexible sides and a puckering mouth at its top, an inner bag composed of flexible material secured to the bottom of said bag and adapted to receive a 75 sponge or other articles, and a series of interior pockets disposed in the wall of said pouch bag around said inner bag and adapted to hold toilet articles in upright position against the inner bag which serves as a cushion for said pocket when the pouch bag is closed and to lie in inclined exposed position when the mouth of the pouch bag is open. 80

JOHANNES SAHL.
